WOOL SCOURING

Leo D. Jones, Philadelphia, Pa., assignor to The Sharples Specialty Company, Philadelphia, Pa., a Corporation of Delaware

Application June 8, 1929. Serial No. 369,280

4 Claims. (Cl. 87—6)

This invention relates to wool scouring, and particularly to a process and apparatus whereby the liquor in the scouring bowls is maintained in effective condition and grease, dirt, and soluble substances are continuously recovered from the liquor, the grease being recovered in desirable condition and in a substantially dry state. The term "wool" is used herein to designate the hairy coat of various animals of which sheep are but an example.

Raw wool contains undesirable substances which must be removed before the wool is used and which may constitute as much as 75% of the weight of the wool and which include grease or degras, soluble organic substances, some of which are potassium compounds, and dirt. To effect removal of these substances the wool is scoured in a hot aqueous solution of sodium carbonate and soap and rinsed; and if it is desired or necessary that the grease and soluble substances be recovered, they must be separately recovered free of dirt from the scouring liquor and rinsing water. In view of the large quantities of material to be removed from the wool in the scouring operation, the scouring liquor and rinsing water are rapidly contaminated and their effectiveness is rapidly impaired. And, in view of the relatively high temperature of the scouring liquor, decomposition occurs, and delays in removal therefrom of substances removed from the wool thereby will result in decomposition, particularly of the grease, and cause the recovered grease to be dark in color and otherwise impaired in quality.

A feature of this invention is that removal of grease and dirt from the scouring liquor is continuous, with the result that the degree of purity and effectiveness of the scouring liquid is maintained uniform and relatively high. Another feature of this invention is that the concentration in the scouring liquor with which the scouring operation is being carried on, of water-soluble substances thereby removed from the wool, may be controlled, with the result that after the scouring operation has proceeded for some time with a fresh batch of liquor the substances dissolved therein from the wool may be utilized to effect the results obtained by the use of soap in the liquor and the necessity for further addition of soap is minimized or eliminated. Other features of this invention are that fresh water is added to the system to compensate for liquor taken out in the wool and for liquor lost, or discarded for the purpose of controlling the concentration of soluble substances, in the puri-

fying of the scouring liquor; and that water so added is introduced into a later rinsing operation and rinsing water is flowed countercurrent to the path of the wool through the scouring train, as its content of soap, soda and soluble impurities increases, to the scouring operation, the liquor in the scouring operation being subjected to continuous purification. Additional features of my invention reside in the steps and apparatus whereby the liquor in the scouring and rinsing steps flows countercurrent to the path of the wool.

It has been proposed to pass into a centrifugal separator scouring liquor charged with grease, soluble substances removed from the wool, and dirt, and to separately discharge the grease and aqueous solution, while retaining the dirt in the bowl; but centrifuges rotated at sufficient speed to effect separation of grease from the aqueous solution possess such limited capacity for retained dirt, that such centrifuges must be stopped and cleaned several times each hour, and the separate discharge of grease and aqueous solution while retaining dirt in the bowl is wholly impracticable commercially. Such a centrifugal separating operation, because of the necessity for cleaning the centrifugal bowls, is adaptable neither to continuous purification of scouring liquor nor to batch purification thereof.

A feature of this invention is that the purification of the scouring liquor is effected centrifugally as well as continuously. Other features of this invention are that as a result of the centrifugal purification involved, the scouring liquor is maintained sufficiently pure to be effective and the grease may be recovered in a substantially dirt-free and dry state, and the soluble substances removed from the wool may be recovered economically. Another feature of this invention is that the operations involved in such purification are carried on with such promptness that the character of the substances recovered is not impaired. The features last mentioned include numerous details that are part of this invention. The scouring liquor is withdrawn from the scouring operation at a point at which the concentration therein of grease, soluble substances and dirt is at a maximum or relatively high. The withdrawn liquor is so treated centrifugally that substantially all of the dirt and a part of the grease are removed, in a centrifugal operation in which the removal of dirt neither interrupts the operation of the centrifuge to any objectionable extent nor requires large numbers of centrifugal machines and

attendants, and then the resulting purified liquor is returned to the scouring operation. To this end the withdrawn liquor is subjected to a centrifugal operation which produces an effluent having an increased concentration of grease and an effluent having a reduced concentration of grease and results in an accumulation of dirt in the centrifuge, the centrifuge being so designed and constructed as to permit of the 5 accumulation of large quantities of dirt without impairment of its operation, and to permit of the removal of that dirt with but momentary interruption of operation. The effluent that contains a reduced content of grease and is substantially free of dirt is returned to the scouring 10 operation without substantial loss of heat. Thus, the liquor in the scouring operation is subjected to a continuous withdrawal of liquor containing a high concentration of substances 15 removed from the wool, and that liquor is returned to the scouring operation after being substantially freed of dirt and after its concentration of grease is reduced and while it contains substantially the same concentration of 20 detergents as the liquor in the scouring operation, or substantially the same concentration of detergents as it contained when it was withdrawn from the scouring operation, such detergents being sodium carbonate and soap or soluble 25 substances withdrawn from the wool and effective as detergents. This operation will maintain the scouring liquor in effective condition and prevent the concentration of grease and dirt therein from exceeding a predetermined 30 maximum.

Another feature of this invention is that the effluent containing the higher concentration of grease but substantially free of dirt is subjected to a second centrifugal operation capable of 35 effecting a separation of the grease from the aqueous solution. Centrifuges of the type that must be used for such a separation would clog so rapidly with dirt; if liquor containing substantial 40 quantities of dirt were fed to them, that such use of them would be impractical. One effluent of this separating operation may be referred to as wet grease in that it contains 90% or more of grease, and water. The other effluent of this 45 second centrifugal operation, which may be referred to as the aqueous effluent, is substantially free of grease but contains some soap and soda and also soluble substances removed from the 50 wool. These soluble substances are of value, particularly as fertilizer. This aqueous effluent 55 may be returned to the scouring operation unless such return would result in building up to an undesirable degree the concentration in the scouring liquid of soluble substances removed 60 from the wool; and, if so, the recovery of soluble substances removed from the wool is readily effected by recovering those substances from this aqueous effluent. In this connection it is a feature of my invention that this second centrifugal 65 operation may be carried on, in whole or in part, in such a manner that the aqueous effluent is substantially free of grease if it is not to be returned to the scouring operation. And, another feature of my invention is that the soluble 70 substances removed from the wool may be recovered from this aqueous effluent that contains a minimum of grease, by utilizing this effluent in the production of steam for the various heating operations in the practice of this invention, 75 such as the heating of the scouring liquor and

the heating of various bodies of material in the purifying operation.

Another feature of this invention is that the wet and substantially dirt-free grease obtained in the second centrifuging operation is by washing freed of detergents and of soluble substances removed from the wool, and is, by a third centrifugal step, converted into substantially dry clean grease.

In prior practise in wool scouring the scouring liquor was frequently subject to continual dilution, requiring frequent addition of detergents; and large batches of liquor accumulated that contained too much dirt and grease for further use; and frequently the liquor was objectionably dirty throughout a considerable part of the scouring operation. Purification of batches of discarded liquor has proved so difficult that deterioration occurs before the grease can be recovered. In contrast, in the practice of this invention, the same liquor may be retained in the scouring bowls for several days and the concentration of dirt never exceeds a predetermined maximum and the scouring operation is uniform. Moreover it is possible in the practice of this invention to maintain, without having an undesirable dirt content in the scouring liquor, such a concentration of soluble substances removed from the wool that addition of soap to the liquor is unnecessary or is minimized. And, in the practice of this invention little personal attendance is necessary and it is possible to recover the grease and soluble substances economically; and any liquor that must be discarded is sufficiently pure to avoid extensive 100 contamination of streams.

Other and further features and advantages of this invention will be apparent from this description taken in connection with the accompanying drawings which show one embodiment of my invention to which my invention is not limited and in which,

Fig. 1 shows diagrammatically apparatus embodying my invention and whereby my process may be practised;

Fig. 2 shows in vertical section a centrifugal machine useful in the practice of my invention;

Fig. 3 shows in front elevation the apparatus shown in Fig. 2; and

Fig. 4 is a detail.

Referring to the drawings a series of scouring bowls 10, 11, 12, etc. may be employed, which are not materially different from scouring bowls now in use, and of which four or five or more may be employed in series. Each scouring bowl comprises a tank open at the top and having its bottom formed into sediment collecting compartments 14 and having across its interior a perforated plate or screen 15 along which is advanced the wool to be washed and through which insoluble substances drop. The wool is introduced into the respective bowls in any suitable manner as by means of belt conveyors 16, 17, 18, etc.; and the wool is advanced along the screen 15 in each scouring bowl in any suitable manner, as by means of rakes 19, the teeth of which are moved by known mechanism in paths indicated by the dotted line 20. Having sufficient aqueous solution of soap and sodium carbonate in bowl 10 to maintain the level of liquid therein approximately at the line 21 wool is fed to the conveyor 16 from which it falls into bowl 10 and is advanced throughout the length thereof until it slides over the weir 22 and between the wringer rolls 140

23 which expel liquor that is caught in tank 24, and from rolls 23 the wool is taken by conveyor 17 and dropped into bowl 11 where it is similarly advanced until it is wrung by rolls 25, the liquid thereby removed being caught in tank 28. Then, the wool is taken by conveyor 18 and deposited in bowl 12, this procedure continuing until the scoured wool is finally discharged from the last bowl. The second bowl 11 contains sufficient detergent, usually soap, to complete the scouring of the wool and to retain the grease in emulsified form; and succeeding bowls in the scouring train contain rinsing water. From tank 24, liquor removed from the wool by rolls 23 passes through pipe 27 into tank 28. Liquid from tank 28 is passed by pump 29 through pipe 30 back into bowl 10 and into contact with dry wool deposited therein by conveyor 16. This spray of liquor wets the wool causing it to sink in the scouring liquor. Without the spray it might not be wetted and would float. Similarly each successive scouring or rinsing bowl 11, 12, etc. is provided with a tank, such as tank 28, for collecting liquor removed from the wool by the wringer rolls, and that liquor passes through pipe 35 into a tank 36 from which it is withdrawn by pump 37 and passed through pipe 38 back into the bowl from which it came unless diverted to an earlier bowl of the train as hereinafter described.

30 From the bottom of each settling compartment 14 of bowl 10 liquor containing grease, dirt and soluble substances removed from the wool, is passed through valves 31 into pipe 32 to pump 33, which passes the withdrawn liquor through pipe 34 to the purifying operation from which a part of the liquor is returned as heretofore stated and as hereafter more clearly described.

40 From scouring bowl 10 liquor is withdrawn through pipe 32 for purification and all of that liquor is not returned to the bowl and liquor is carried out in wet wool that entered that bowl in a dry state. To compensate for this, pipe 39 leads from pipe 38 to tank 28 and flow from pipe 39 is controlled by float valve 40. Pipe 38 is also provided with a valve 41 that will ordinarily permit of enough, or more than enough, flow of liquor of make-up for removal of liquor from bowl 10 by discharge of wet wool therefrom and by loss or discard of liquor in the purifying operation, but if there is a sudden draught of liquor from bowl 10, as in the case of the starting up or resumption of the purifying operation, then valve 41 limits the rate at which the liquor is advanced from bowl 11 to bowl 10 and allows the deficiency in bowl 10 to be made up gradually with the result that the operation of the entire system is more uniform. 50 Deficiencies of liquor in bowl 11, 12, etc. are made up by flow of liquor from pipe 38 of the respectively preceding bowl into the proper one of tanks 36. Sodium carbonate and soap are supplied to bowl 10 and also to bowl 11 for the purpose of completing the scouring therein and maintaining the grease in an emulsified state. In bowls 12, etc. there will usually be only a rinsing operation, and fresh water is supplied to the last, or any of such bowls, as by means of fresh water-supply pipe 42.

70 The maintenance of sufficiently pure and effective scouring liquor in the scouring bowls, and also the maintenance of sufficiently pure rinsing water in the rinsing bowls, is dependent upon the nature and effectiveness of the continuous

purifying operation. The liquor withdrawn from bowl 10 for purification is passed to a centrifugal machine, of which a suitable form is shown in Figs. 2 and 3, in which it is divided centrifugally into an effluent substantially free of dirt and containing a reduced concentration of grease, an effluent substantially free of dirt and containing an increased concentration of grease, and a body of dirt retained in the centrifuge. The centrifuge is so constructed that a large quantity of dirt may be retained in the rotor but may be dislodged and removed therefrom rapidly and without stopping of the centrifugal bowl. But, while such a centrifuge will produce an effluent containing a higher concentration of grease it is inadvisable to attempt to withdraw substantially water-free grease therefrom.

75 Thus, the withdrawn liquor is passed from pipe 34 through pipe 45 into an imperforate rotor 46 mounted on shaft 47 that is supported in bearings 48 and rotated in any suitable manner. The rotor 46 comprises hub 49 and side wall 50, and surrounding hub 49 and spaced therefrom is a frusto-conical wall 51 having a flange 52 that lies in spaced relation to the end wall 50 to provide an annular supply passage 53 into which liquor is discharged by pipe 45, and which preferably is provided with vanes 54 to cause liquor to rotate with the rotor. Within the interior of rotor 46 is an annular partition 55 that is supported in any suitable manner as by brackets 56 connected to the peripheral wall of the rotor and to annular partition 55. Partition 55 divides the interior of the rotor into a separating compartment 57 and a discharge compartment 58, which compartments communicate through the annular passage 59 between the outer edge of partition 55 and the inner wall of rotor 46. Supply of liquor to rotor 46 and withdrawal of liquor therefrom will be so regulated as to maintain the liquor in the rotor in the form of a hollow cylinder having an inner surface indicated by dotted line 60. Withdrawal of liquor having an increased grease content from rotor 46 may be effected by skimmer 62 acting upon the surface of liquid in separating compartment 57 and removing an effluent containing a higher concentration of grease. Liquid having reduced grease content may discharge, from compartment 58, over the inner edge of annular end wall 61 of the rotor or it may be withdrawn by skimmer 63, acting upon the liquor in discharge compartment 58, there being effected in either case a removal from the rotor of an effluent having a lower concentration of grease. In this connection it is pointed out that liquor of reduced grease content is thrown to the outer zone of the rotor and passes through passage 59 to compartment 58. Skimmers 62 and 63 act upon the surface of the rotating bodies of liquid as shown in Fig. 4, and are mounted for adjustment to various distances from the axis of the rotor. Thus, each skimmer slides in brackets 64 mounted on the casing 6 of the rotor and is provided with a threaded lug 65 in which is threaded a hand-operated shaft 66 that also passes through brackets 64 and is held from longitudinal motion therein by means of collars 67 that are secured to shaft 66. Thus rotation of shaft 66 effects the adjustment of the position of the skimmers to points along a radius of the rotor.

80 Liquid withdrawn by skimmer 63 and which is freed of dirt and contains a reduced grease con- 85 90 95 100 105 110 115 120 125 130 135 140 145 150

tent is passed through pipes 68 and 69 back to scouring bowl 10. Liquid discharged over edge 61 into casing 6 drains through pipe 7 into pipe 69. Liquid withdrawn by skimmer 62 and which 5 is freed of dirt and contains an increased concentration of grease is passed by pipe 70 to a collecting tank 71 for further treatment.

After a considerable quantity of dirt has accumulated in the rotor 46, valve 8 is closed, thus 10 cutting off the supply of liquor to rotor 46, and valves 72 and 73 are closed, and valves 74 and 75 are opened, thus cutting off return of one effluent to bowl 10 and flow of the other effluent to tank 71 and diverting both effluents to reservoir 76, and skimmer 63 is moved radially outward in rotor 46, effecting removal of liquid from rotor 46 to reservoir 76. During such complete removal some dirt may be removed by skimmer 63 and therefore that liquor is passed to reservoir 15 76 instead of being returned to bowl 10 or passed to tank 71. Then, by means of tool 77, which may be operated in any known manner, for example as shown in the application of Laurence P. Sharples, Serial No. 174,975, filed 20 25 March 12th, 1927, the dirt is dislodged from the rotor during rotation thereof, and it falls into hopper 78 and is collected in some receptacle such as box 79. Then valve 80 which is normally closed, is opened and the dirty liquor that is temporarily held in reservoir 76 is fed to the 30 35 rotor through pipe 45 for centrifugal treatment. When tank 76 is empty, valve 80 is closed, valve 8 is opened, and continuous purification is resumed.

Liquid in tank 71, which has a higher concentration of grease and is free of dirt, is heated, as by steam coil 88, to a higher temperature that will facilitate separation of grease from aqueous solution. Then it is passed through pipe 81 to super centrifuge 83 which may be of the type shown in Sharples Patent No. 1,320,419, and which may be rotated at speeds of the order of 15,000 R. P. M. One effluent from this centrifuge consists of wet grease, containing about 40 45 10% of water, discharged through spout 84 and collected in bucket 85. The other effluent, discharged through spout 87 into tank 103, consists of an aqueous solution of soluble impurities removed from the wool, and is of low grease content. This aqueous effluent will have about the same concentration of detergents as the scouring liquor in bowl 10, but will be practically free of insoluble material.

The wet grease obtained in this second centrifugal operation is transferred to washing tank 89, as by means of bucket 85. In this tank the wet grease is mixed with about three to five times its volume of water, as by means 55 60 65 of cold water supplied by pipe 90 to tank 91 under the control of float valve 92, the water flowing through pipe 93 from tank 91 to tank 89. Steam coil 94 heats the contents of tank 89 and the added water so dilutes the soap content of the grease that in further treatment of the resulting mixture in super-centrifuge 95, to which the mixture is led by pipe 96 or pipe 97, the grease emulsion is broken down and the grease becomes continuous and free of water 70 75 and is discharged through spout 98 as dry grease containing but a fraction of a percent of water. The aqueous component of the mixture is discharged through spout 99 from which it may be passed by pipe 100 back to that one of the bowls of the scouring train in which the liquor is of similar composition.

The scouring liquor is continuously separating grease from the wool and taking up soluble substances from the wool in the scouring operation. The scouring liquor in the scouring operation is maintained at a desired degree of purity by continuously withdrawing grease therefrom and by continuously discarding some of the liquor, which is replaced by fresh water, that contains soluble substances taken up from the wool and contains a minimum proportion of grease. 80 85 90 95 100 105 110 115 120 125 130 135 140 145 150 Scouring liquor is continuously drawn from the scouring operation and subjected to centrifugal separation and an effluent of that separation which contains a reduced grease content is continuously returned to the scouring operation. The rate at which this step is carried out is so regulated as to maintain a sufficiently low grease content in the scouring liquor in bowl 10. When insoluble solids are dislodged from rotor 46 they carry with them some liquor in which soluble substances removed from the wool are in solution. The amount of scouring liquor so withdrawn from the liquor in circulation may be sufficient to maintain a desirably low concentration of soluble substances in the scouring liquor. If not, all or part of the aqueous discharge from centrifuge 83, and which contains soluble substances removed from the wool, may be discarded from the system, as by discharge through drain 101 of tank 102 into which the aqueous effluent of centrifuge 83 may be conducted through pipe 116. When the operation of the purifying system is so adjusted that grease is flowing into the buckets 85 at a sufficiently rapid rate to maintain at a sufficiently low value the concentration of grease in scouring bowl 10, the amount of aqueous solution discharging through spout 87 may be greater than the amount thereof that must be discarded in order to maintain a sufficiently low concentration of soluble substances in a scouring liquor. In such case that part of the aqueous solution produced by the second centrifuging operation which need not be discarded for the purpose of keeping down the concentration 120 of soluble substances in bowl 10, is returned to the scouring train as by being passed from tank 103 by means of pipes 104, 105 and 106 to scouring bowl 10 or 11, according to which bowl contains scouring liquor having a composition most like the aqueous effluent collected in tank 103.

Liquor that is so discarded contains water-soluble substances removed from the wool and those substances can only be recovered by evaporation of the solution. However, the solution is very dilute and the cost of evaporating it is greater than the value of the substances in it. It is a feature of this invention that these substances are recovered, and it is a further feature of this invention that the recovery of these substances is effected without materially increasing the cost of the operation of the purifying steps described, although it has been economically impracticable heretofore to recover these water-soluble substances. To this end it is a feature of this invention that aqueous effluent from the second centrifugal operation is fed to an evaporator 107 that is heated in any suitable manner as by burner 108 and the resulting steam is fed by pipe 109 to heating coils 88 and 94 and by pipe 110 and branches 111 to the scouring liquor or rinsing water in the several bowls of the scouring train in order to maintain them at a suitable temperature, e. g. 130° F. Concentrated soluble impurities are withdrawn from the evaporator by 150

pipe 112. Inasmuch as it is desirable that aqueous solution passing to the evaporator should be as free as possible of grease, a second centrifuge 82 may be included in the second centrifuging 5 operation and operated at low capacity in order to insure a maximum of grease removal from the aqueous effluent passing therefrom through spout 86 into tank 102 from which the aqueous solution is passed by pump 114 to evaporator 107. Grease 10 discharged through spout 115 may be collected in bucket 85 and conveyed to tank 89. It is to be expected that the passing of all aqueous solution from spout 86 to evaporator 107 will effect 15 sufficiently rapid removal of soluble substances from the scouring liquor, but if not, additional aqueous solution may be passed to evaporator 107 from tank 103 by means of pipe 116.

In the operation of this invention it is to be understood that soap and sodium carbonate are 20 to be added to the scouring bowls as required, scouring bowl 10 usually containing five or ten times as much soap as scouring bowl 11, and scouring bowl 10 containing about as much sodium carbonate as it does soap. Throughout 25 the apparatus valves are employed as required and as indicated in the drawings.

To assist in the understanding and practice 30 of this invention, but with the intention that my invention is not limited to the proportions described in this example, an actual operation of this invention was as follows:

In this operation wool was scoured at the rate 35 of one thousand pounds per hour, the wool being Colorado wool. Three thousand gallons of liquor were maintained in the first scouring bowl. The scouring and purifying operations above described were carried out, and after a few hours of operation the concentration of impurities in the scouring bowl ceased to increase; and at this 40 equilibrium point the scouring liquor in the first bowl contained 0.5% of soap, 0.3% of sodium carbonate, 1.0% of grease, and soluble impurities and dirt removed from the wool. Thus in the scouring of this Colorado wool the purifying 45 operation was capable of maintaining this low degree of impurity in the scouring liquor of the first bowl. In the operation described one thousand gallons of liquor per hour were withdrawn from the first scouring bowl and passed to the purifying operation. In the first 50 centrifuging operation this withdrawn scouring liquor was divided into a first fraction constituting 70% of the withdrawn liquor and containing .05% of grease, and a second fraction 55 constituting 30% of the withdrawn liquor and containing 2.2% of grease. Dirt was removed from the first centrifuge once each hour to the extent of about two hundred pounds each hour. The first fraction, in view of its composition, 60 was returned to the first scouring bowl. The difference between the one thousand gallons per hour withdrawn from the first scouring bowl and the 700 gallons per hour so returned thereto was made up by counterflow of liquid from the succeeding bowls of the train to the first bowl. The second fraction was passed on to the second centrifuging operation in which it was divided into a wet-grease fraction consisting 65 of about 95% grease and a second fraction containing 0.2% grease. The second fraction was evaporated and as a result it was found that the

withdrawn scouring liquor contained 3% to 4% of soluble impurities. The aqueous solution withdrawn from the second centrifuge for the purpose of recovering soluble impurities may be treated in a spray drying operation for the purpose of obtaining those impurities in a substantially dry state. The wet-grease fraction after washing and centrifugal treatment consisted of about 50 pounds of dry grease for each one thousand pounds of liquor withdrawn from the 80 scouring bowl. The wool scoured in the operation described was an example of a fairly clean wool prior to scouring. 85

I claim:

1. In apparatus for scouring wool, a series 90 of scouring bowls adapted for the passage of wool successively therethrough, a wringer associated with each bowl and adapted to wring wool passing therefrom, a tank associated with each bowl and with the wringer associated therewith and adapted to collect scouring liquor removed from the wool thereby, a pipe leading to each tank from the tank associated with the next succeeding bowl and provided with a valve, a float in each tank for controlling said valve, 100 in said pipe leading thereto, and means for passing liquor to each of said bowls of said series from the tank associated therewith.

2. In apparatus for scouring wool, a series of 105 scouring bowls adapted for the passage of wool successively therethrough, a wringer associated with each bowl and adapted to wring wool passing therefrom, a tank associated with each bowl and with the wringer associated therewith and adapted to collect scouring liquor removed from the wool thereby, a pipe leading to each tank from the tank associated with the next succeeding bowl and provided with a valve, a float in each tank for controlling said valve in said pipe leading thereto, means for supplying fresh 115 liquid to the last of said bowls, and means for withdrawing contaminated liquid from the first of said bowls.

3. In apparatus for scouring wool, a scouring 120 bowl, means for separating scouring liquor into dirt-free liquor and dirt, means for passing liquor from said bowl to said means, a high-speed centrifugal separator adapted for separating grease from liquor discharged from said first means, pipes for conducting liquor discharged from said first means to said high-speed centrifugal separator, an evaporator for aqueous-solution discharged from said high-speed centrifugal separator, and pipes for conducting steam from said evaporator into heat exchange 125 relation with liquor in said scouring bowl.

4. In an apparatus for scouring wool, a scouring 130 bowl, means for separating scouring liquor into dirt-free liquor and dirt, means for passing liquor from said bowl to said means, a high-speed centrifugal separator adapted for separating grease from liquor discharged from said first means, conduits including a heating tank for passing liquor discharged from said first means 135 to said high-speed centrifugal separator, an evaporator for aqueous-solution discharged from said high-speed centrifugal separator, and pipes for conducting steam from said evaporator into heat exchange relation with liquor in said heating tank.

LEO D. JONES.
